RAILWAY CAR

Filed Aug. 28, 1929 2 Sheets-Sheet 2

UNITED STATES PATENT OFFICE

WILLIAM E. WINE, OF TOLEDO, OHIO

RAILWAY CAR

Application filed August 28, 1929. Serial No. 389,017.

My invention relates to railway cars and more particularly to improvements in the lading discharge doors thereof and it has for its principal object the provision of simple and rugged means for reinforcing and stiffening such doors.

Another object of the invention is to provide means for rigidly connecting the stiffeners of each door.

10 A primary feature of the invention consists in providing the door with a stiffening member having a portion secured thereto and a portion extending outwardly beyond the adjacent side of the car, said member 15 having a top flange and a portion substantially normal thereto, the portion of the flange underlying the door projecting from one side of the normal portion and the portion of the flange extending beyond the side 20 of the car projecting from the opposite side of the said normal portion.

Another feature of the invention consists in providing the door stiffening member with reversely disposed channel sections, 25 one of said channel sections underlying and being secured to the door and the other of said channel sections being disposed outwardly of the adjacent side of the car for co-operating with mechanism for supporting the door in closed position.

A further feature of the invention consists in providing improved means for rigidly connecting those portions of the stiffening members of each door which are 35 spaced downwardly from the floor of the car.

Other and more specific features of the invention residing in advantageous forms, combinations and relations of parts will 40 hereinafter appear and be pointed out in the claims.

In the drawings illustrating a preferred embodiment of the invention:

45 Figure 1 is a fragmentary plan view, partly in section, of a gondola car showing the invention applied thereto.

Figure 2 is a fragmentary side elevational view of the construction illustrated in Figure 1.

Figure 3 is a sectional view taken on line 3—3, Figure 1.

Figure 4 is a plan view of one of the door stiffeners.

Figure 5 is an end view of the stiffener. 55

Figure 6 is a sectional view taken on line 6—6, Figure 4.

For purposes of illustrating the invention a gondola car having wooden lading discharge doors has been chosen, but it will 60 be understood as the specification proceeds that the invention is not limited in its application to cars or doors of these types. Furthermore, since the construction of the 65 stiffeners applied to each door of the car is the same, only one door and the portion of the car construction immediately adjoining it has been illustrated.

Referring more particularly to the drawings, 1 indicates one of the car center sills 70 and 2 a side sill of the car. The floor 3 of the car, which rests upon and is supported by these sills, is provided with a plurality of lading discharge openings, one 75 of which is shown at 4. The wooden sides 5 of the car are strengthened and reinforced by side stakes 6 and diagonally extending braces 7 which are preferably rigidly secured to the adjacent side sill by rivets 8.

The doors 9 for closing the lading 80 discharge openings, are hingedly connected to the car adjacent the center sills in a manner to be hereinafter described and each preferably comprises a plurality of planks or boards rigidly connected by stiffening members 10. To prevent the escape of fine lading 85 between the doors and the portions of the floor bounding the door openings, metal strips 11, or the like, may be conveniently employed, the strips being secured to the floor so that portions thereof will overlap the top surface of the door when the latter is in closed position.

Each of the door stiffening members 10 has offset or spaced portions 12 and 13, re- 95 spectively, the former underlying and being secured to the door and the latter being spaced below the car floor to project beneath the adjacent side sill and outwardly beyond the car side. These portions of the door 100

stiffeners are respectively connected by inclined portions 14 and all portions of the stiffeners are formed with upper and lower flanges 15 and 16, respectively, connected by web portions 17 arranged substantially normal thereto. The portion of the flange 15 of each of the stiffeners which underlies the door is formed with a plurality of apertures for receiving bolts 9^a employed to secure the stiffeners to the planks comprising the door.

To hingedly connect the door to the car body the inner end of each stiffener may advantageously be integrally formed with an apertured portion 18 to cooperate with a hinge pin 19 carried by a bracket 20 rigidly secured to the adjacent center sill 1. At their opposite ends the flanges 15 of the stiffeners are adapted to respectively co-operate with mechanisms 21 employed to support the door in closed position. Each of these mechanisms comprises a pivoted hook 22 having a shoulder adapted to engage the under side of the flange 15. Since it is desirable to hingedly connect the door to the car body at points spaced a relatively great distance apart, the stiffening members are secured to the door adjacent its side edges. However, in order that the diagonal braces 7 and appurtenances with which the side of the car may be provided will not interfere with the mounting and free operation of the door supporting mechanisms 21 it is necessary that the projecting ends of the stiffeners be brought closer together than the hinged ends thereof. Furthermore, it is desirable that the door supporting mechanisms be relatively close together, as then a practically three point support is provided for the door and the advantages of supporting the door at three points are, of course, well known.

To accomplish this purpose, namely, to space the hinged ends of the door stiffening members a greater distance apart than the ends thereof which co-operate with the door supporting mechanisms, the downwardly inclined portions 14 thereof converge toward each other, while the respective portions 12 and 13 of the members are preferably arranged so as to parallel each other.

As offsetting the stiffeners so as to cause them to converge toward each other tends to impair their rigidity and to subject them to eccentric loadings, the portion of the upper flange of each, which underlies the door, projects from the web portion 17 in a direction opposite to that in which the portion of the upper flange that co-operates with the pivoted door supporting hook projects therefrom. By arranging these portions of the flanges in this manner the inner and outer ends of each stiffener may be transversely offset the desired amount with a minimum

distortion or offsetting of the web portion 17. It will thus be seen that the stiffeners are each provided with reversely disposed channel sections and that they are secured to the door so that the flanges of the channel sections which underlie the door project away from each other, while the flanges of the channel sections which are spaced below the car floor project toward each other.

At the points where the webs 17 of the stiffeners converge toward each other the upper and lower flanges project from both sides thereof, as on opposite sides of the points of convergence the webs respectively connect opposite marginal edges of the flanges. Thus, the amount of convergence of the flanges of the stiffeners is greater than that of the webs, thereby keeping to a minimum the impairment of rigidity and the eccentric loading of the stiffeners arising from the transverse offset formed in each.

The portions of the stiffeners which are spaced below the car floor are rigidly connected so as to prevent their relative displacement. The means employed for this purpose may comprise an angle shaped member 23 having legs or flanges 24 and 25, respectively. The opposite ends of the leg 24 are adapted to underlie and be rigidly secured by rivets 26 to adjacent portions of the top flange 15 of the stiffeners, while opposite ends of the flange or leg 25 are rigidly secured by rivets 27 to portions 28 which are integrally formed with the stiffeners and project laterally therefrom substantially normal to adjacent portions of the respective top flanges 15. By connecting the stiffeners in this manner it will be readily perceived that their outer ends are tied together in a most effective manner.

The foregoing construction results in the production of strong and rugged members, which, in addition to serving as means for stiffening the door, also function to co-operate with means for pivotally connecting it to the car body and for supporting it in closed position.

I claim:

1. In a railway car having a lading discharge opening, the combination with a door for closing said opening, of a stiffening member for the door having a top flange and a portion substantially normal thereto, a portion of said flange being secured to the door and a portion thereof being adapted to co-operate with mechanism for supporting the door in closed position, the portion of the flange secured to the door projecting in one direction from the normal portion of the stiffening member and the portion of the flange adapted to co-operate with the door supporting mechanism projecting in the opposite direction from the said normal portion.

2. In a railway car having a lading dis-

charge opening, the combination with a door for closing said opening, of a stiffening member for the door having a top flange and a portion substantially normal thereto, said member being inclined downwardly and outwardly intermediate its ends to project beyond the adjacent side of the car, the portion of the flange on one side of said incline projecting in one direction from the normal portion of the member, the portion of the flange on the other side of said incline projecting in the opposite direction from the said normal portion and the portion of the flange at the incline of said member projecting in both directions from the said normal portion.

3. In a railway car having a lading discharge opening, the combination with a door for closing said opening, of a plurality of stiffening members secured to the underside of the door and projecting beyond a side of the car for cooperation with mechanism to support the door in closed position, the portions of the stiffening members underlying the door being of substantially channel shape and arranged so that their flanges extend away from each other, the outwardly projecting portions of the members being also of channel shape and being arranged so that their flanges extend toward each other.

4. In a railway car having a lading discharge opening, the combination with a door for closing said opening, of a stiffening member for the door having a plurality of flanges and a web, said member being secured to the underside of the door and extending outwardly beyond the side of the car for cooperation with mechanism to support the door in closed position, the flanges of the portion of the member underlying the door projecting from the web in a direction opposite to that in which the flanges of the outwardly projecting portion of the member project therefrom.

45 5. In a railway car having a lading discharge opening, the combination with a door for closing said opening, of a stiffening member for the door having a plurality of flanges and a web, said member being secured to the door and being inclined downwardly and outwardly intermediate its ends to project beyond an adjacent side of the car for cooperation with mechanism to support the door in closed position, the flanges of the portion of the member underlying the door projecting from the web in a direction opposite to that in which the flanges of the outwardly projecting portion of the member project therefrom and the flanges on the inclined portion of the member projecting in both directions from the web.

60 6. In a railway car having a lading discharge opening, the combination with a door for closing said opening, of a plurality of flanged door stiffeners respectively having

spaced portions disposed in substantially parallel planes, the spaced portions of each of said stiffening members being connected by portions which converge toward each other, corresponding parallel portions of said members being respectively provided with flanges projecting away from and toward each other. 70

7. In a railway car having a lading discharge opening, the combination with a door for closing said opening, of a plurality of door stiffeners respectively having spaced portions disposed in substantially parallel planes, the spaced portions of each of said stiffening members being connected by portions which converge toward each other, corresponding parallel portions of said members being respectively provided with flanges projecting away from and toward each other, 75 so

8. In a railway car having a lading discharge opening, the combination with a door for closing said opening, of a plurality of stiffening members secured to the door, each of said members having a portion spaced below the floor of the car and projecting beyond the adjacent side of the car for cooperation with mechanism to support the door 90 in closed position, the downwardly spaced portions of the members being respectively provided with top flanges, and means rigidly secured to the underside of the said top flanges for rigidly connecting the said 100 downwardly spaced portions of the members.

9. In a railway car having a lading discharge opening, the combination with a door for closing said opening, of a plurality of stiffening members secured to the door, each of said members having a portion spaced below the car floor and projecting beyond an adjacent side of the car for cooperating 105 with mechanism to support the door in closed position, the downwardly spaced portions of said members being respectively provided with angularly disposed portions, and means rigidly secured to said angularly disposed portions for connecting the downwardly spaced portions of the members. 110

10. In a railway car having a lading discharge opening, the combination with a door for closing said opening, of a plurality of stiffening members secured to the door, each of said members having a portion spaced below the car floor and projecting beyond the adjacent side of the car to cooperate with mechanism for supporting the door in closed 120 position, said downwardly spaced portions of each member having a top flange and a portion substantially normal thereto, and a flanged member rigidly secured to said top flange and said normal portion of each mem- 125 130

ber for connecting the downwardly spaced portions thereof.

11. In a railway car having a lading discharge opening, the combination with a door for closing said opening, of a plurality of stiffening members secured to the door, each of said members having a portion spaced below the car floor and projecting outwardly beyond an adjacent side of the car for cooperating with mechanism to support the door in closed position, and an angle member connecting said downwardly spaced portions of the stiffening members, each flange of said angle member being rigidly secured to each

10 stiffening member.

15 12. In a railway car having a lading discharge opening, the combination with a door for closing said opening, of a plurality of stiffening members respectively provided

20 with top flanges and portions substantially normal thereto, said members having spaced portions arranged substantially parallel with each other, one of said portions of each member being secured to the door and 25 the other projecting outwardly beyond an adjacent side of the car for cooperating with mechanism to support the door in closed position, the spaced parallel portions of the members being respectively connected 30 by downwardly inclined portions which converge toward each other, the convergence of the top flanges of said inclined portions being greater than the convergence of the normal portions thereof.

35 13. In a railway car having a lading discharge opening, the combination with a door for closing said opening, of a plurality of stiffening members for the door respectively provided with flanges and webs, each of said members having a portion secured to the door and a portion projecting outwardly beyond the adjacent side of the car for cooperating with mechanism to support the door in closed position, said portions of 40 the members being respectively connected by 45 downwardly inclined portions which converge toward each other, the convergence of the flanges of said inclined portions being greater than the convergence of the webs 50 thereof.

55 14. In a gondola car having a lading discharge opening, the combination with a door for closing the opening, of a stiffening member for the door, said member being provided with reversely disposed channel sections, one of which underlies and is secured to the door and the other of which projects outwardly beyond an adjacent side of the car for cooperation with mechanism to support the door in closed position, said member being provided with means for pivotally connecting the door to the car body.

60 In testimony whereof I affix my signature.
